UNITED STATES PATENT OFFICE

152,765

DESIGN FOR A CARTON

Joseph Binder, New York, N. Y., assignor to Pepperell Manufacturing Company, Boston, Mass., a corporation of Massachusetts

Application May 1, 1946, Serial No. 129,192

Term of patent 3½ years

(Cl. D58—12)

To all whom it may concern:

Be it known that I, Joseph Binder, a citizen of the United States of America, residing at New York, in the county of New York and State of New York, have invented a new, original, and ornamental Design for a Carton, of which the following is a specification, reference being had to the accompanying drawing, forming a part thereof, in which:

Fig. 2 is a perspective view of the carton embodying my new design.

I claim:

The ornamental design for a carton, as shown.

JOSEPH BINDER.
